UNITED STATES PATENT OFFICE

AUGUST KOPPERS, OF BOCHUM, GERMANY

RECORDING MECHANISM FOR COKE-OVEN PUSHERS AND THE LIKE

Application filed September 11, 1930, Serial No. 481,096, and in Germany February 12, 1930.

My invention relates to recording appliances for coke-oven pushers and the like, which give a complete record of the operation of the pusher.

- 5 It is an object of my invention to improve appliances of this type as hitherto designed. To this end, instead of arranging the recording instrument on the pusher, as has already been suggested, I provide a stationary recording instrument and means connected with the pusher and parts thereof for operating it.
- 10 I have found that the records obtained with instruments installed on the pusher are not as exact as they should be, because the instruments are disturbed by the vibrations of the pusher moving on its track past the battery of ovens and also by the slip of the pusher driving wheels on the track. These disturbances are eliminated according to this
- 15 invention by fixing the recording instrument on the ground.
- 20 In the drawings affixed to this specification and forming part thereof a pusher and recording mechanism embodying my invention are illustrated diagrammatically by way of example.

In the drawings

Fig. 1 is a partly sectional elevation, and Fig. 2 a diagrammatical plan view of the

- 25 pusher.
- Fig. 3 is an elevation of the stationary recording instrument with part of the casing removed, and

Fig. 4 is a record.

- 30 Referring now to the drawings and first to Figs. 1 and 2, 1 is a track extending in front of a battery 2 of coke ovens, 3 is the frame of the pusher and 4 are the wheels on which it runs on the track 1. The means for moving the pusher along the track and for operating its mechanisms are not fully but diagrammatically illustrated, as they do not form part of the invention. Supported to reciprocate in the frame 3 are the extruding bar 5 and
- 35 the levelling bar 6. The extruding bar 5 which at its front end is equipped with a plate 7, is mounted on rollers 8, 8, the levelling bar on rollers 9, 9.

- 40 10 is a sheave which is mounted for rotation about a horizontal axis in a vertical member

11 of the frame. 13 and 14 are guide pulleys in line with the sheave 10, but arranged to rotate about vertical axes on a member 15 at the inner end wall of the pusher. 16 is a stationary vertical pulley at one end of the battery 2, 17 is a stationary vertical sheave at the other end, and 18 is the stationary recording instrument on which the sheave 17 is mounted for rotation. 19 is an endless cable which is placed round the sheave 10, the pulleys 13, 14 and 16 and the sheave 17 of the recording instrument 18. 20 is an arm which is keyed on the shaft of the principal sheave 10 and is weighted at 21. 22 is a transverse bar at the free end of the arm 20, and 23 and 24 are pulleys at opposite ends of the bar 22. The weight 21 normally holds the sheave 10 against rotation so that the cable 19 is anchored on the pusher.

25 is a cable which is attached to the extruding bar 5 at 26 and is wound several times about a pulley 27 on the frame 3 of the pusher, about the pulley 23 on the transverse bar 22, and about a reducing sheave 28, also on the frame 3, its end being weighted at 29 so that the cable is held taut. It is not necessary, but only convenient that 28 should be a reducing sheave, as otherwise the distance through which the weight 29 is raised and lowered would be inconveniently long.

The levelling bar 6 is connected with the pulley 24 at the opposite end of the transverse bar 22 by similar means, 30 being its cable which is attached to the bar 6 at 31, 32 being a pulley on the frame 3 about which the cable is wound several times, 33 being its reducing sheave, and 34 being a weight at the end of the cable 30.

35 Referring now to Fig. 3, the sheave 17 about which the endless cable 19 is wound, imparts rotation to a pair of bevel gears 35 and 36 in the base of the instrument 18. The bevel gear 36 is threaded for the reception of a spindle 37 and held against axial displacement in a bracket 38 so that the spindle is raised and lowered by rotating the bevel gear. 38' is a rod which is connected to the spindle 37 at its upper end, 39 is a stylus at the upper end of the rod 38 and 40 is a record sheet on a drum 41. Suitable

95

100

means (not shown) may be provided for rotating the drum at a given speed.

If, as usual, an electric motor 49 is provided for operating the extruding bar 5, I may combine a recording ammeter with the recording instrument 18 as shown in Fig. 3, 42 being its stylus within the casing of the ammeter, which, like the stylus 39, makes a record on the sheet 40. The amperage for the levelling bar 6 may be recorded in a similar manner.

Means for handling the doors of the ovens in the battery 2 are indicated diagrammatically at 43' in Fig. 2, 44 being the door of oven No. 1.

In operation the pusher 3 is run along the battery on its track 1 and the cable 19 which is retained only by friction on the sheave 10 which is held against rotation by its weight 24, moves with the pusher and records the movement of the pusher on the sheet 40. When the extruding bar 5 (or the levelling bar 6) is operated, the cables 25 and 30, which are attached to the bars 5 and 6, respectively, are entrained and, during the last part of their stroke, raise the arm 20 of the sheave 15, as indicated in dotted lines in Fig. 1, rotating the sheave and moving the cable 19, so that the movements of the bars are recorded on the sheet 14, like those of the pusher itself.

It will be understood from this description that the operation of the pusher is recorded in all its details and by very simple means, without any electromagnetic or other complicated devices, and that the novel mechanism may be adapted to any existing plant. The several stages of operation, such as the removing of the door of an oven, the extrusion of the coke, the levelling of the charge and the reinserting of the door, are plotted against time. The performance and the life of the plant are largely determined by its efficient operation and conditions detracting from its efficiency will be detected on the record.

A record from the new appliance is illustrated by way of example in Fig. 4. The abscissa is divided in hours and quarters, and the movements of the pusher and its bars are the ordinates. Assuming that the pusher has completed a cycle of operations at 1:45, when it is opposite the last oven of the battery, and that it now starts to return to oven No. 1 of the battery, the distance travelled by the pusher into the position for handling the oven door is recorded on the sheet 40 as line *a*—*b*. The sheave 10 does not rotate while this is recorded. The door 44 of oven No. 1 is now moved aside while the pusher stands still for the time *b*—*c*. When the door has been moved aside, the pusher is run in line with the oven (line *c*—*d*), and the extruding bar 5 is advanced. The movement of the extruding bar is only recorded during the

last part of its stroke, that is, after the cable 25 has begun to raise the arm 20 and to rotate the sheave 10. Therefore at first the horizontal line *d*—*e* is recorded and only after the arm 20 has been raised, the instrument will record the extruding operation (line *e*—*f*). This break in the record is due to the fact that only the last stage of the bar operation is recorded, and marks the extrusion as against the motion of the pusher. After the charge has been extruded, the pusher is returned to the position it started from in line with the door (line *f*—*g*) and the door is inserted. Now the charge is levelled by the bar 6. For the reason stated, the operation of this bar, like that of the extruding bar 5, is only recorded during the last stage, that is, when the cable 30 begins to raise the arm 20. The levelling bar is operated repeatedly as shown by the jagged line *g*—*h*. The pusher is now run to the next oven which is ready for extrusion, say No. 6.

Irregularities are recorded also. For instance, when the pusher arrived before oven No. 11, the oven was not ready, as a valve required to be exchanged. In consequence the horizontal line *i* is recorded at this oven, and the pusher is moved on to attend to ovens Nos. 16, 21 and 26. The extrusion was slow at Nos. 16 and 46, as shown by the lines *l*. It is important that such delays be recorded as they must be avoided, for overheating of the extruding bar is undesirable. After No. 26 had been extruded, the repair at No. 11 had been completed, the pusher was returned to this oven, extruded it and then went on to No. 31. A delay occurred before this oven could be attended to, as shown by the horizontal line *k*.

The above shows that the recording appliance operates automatically, does not require any attendance and is not influenced by vibration or other irregularities connected with the running of the pusher, as the instrument 18 is stationary.

While the diagram explained gives a complete record of the operation, it does not disclose the power consumption. It is however desirable that the power demand per oven should also be recorded which is particularly important with coal having a tendency to stick to the oven walls. This is effected by combining with the instrument 18 the recording ammeter 41. Current is supplied to the ammeter by means of slip contacts 46, 47 (shown diagrammatically) and preferably the current supplied to the ammeter is throttled by a suitable resistance 48. For instance the records of the stylus 39 and 42 show that oven No. 46 was extruded at 5:15, and that its maximum power demand was about 120 amps.

I wish it to be understood that I do not desire to be limited to the exact details of the construction shown and described for obvious

modifications will occur to a person skilled in the art.

In the claims affixed to this specification no selection of any particular modification of the invention is intended to the exclusion of other modifications thereof and the right to subsequently make claim to any modification not covered by these claims is expressly reserved.

10 I claim:—

1. A recording mechanism for coke-oven pushers comprising a stationary recording instrument and a pusher machine movable from one to another of a plurality of ovens, means mounted on and movable with the pusher for operating said instrument in conformity with the movements of said pusher and its parts.

2. A recording mechanism for coke-oven pushers comprising a stationary recording instrument, a cable anchored on the pusher and adapted to operate said instrument as the pusher moves, an extruding bar on the pusher and means operatively connected with said bar for imparting movement to said cable.

3. A recording mechanism for coke-oven pushers comprising a stationary recording instrument, a cable anchored on the pusher and adapted to operate said instrument as the pusher moves, an extruding bar on the pusher, a levelling bar on the pusher and means operatively connected with said bars for imparting movement to said cable.

4. A recording mechanism for coke-oven pushers comprising a stationary recording instrument, a sheave mounted to rotate on said pusher, means for holding said sheave against rotation, an endless cable supported in frictional contact with said sheave so as to move with said pusher and operatively connected with said instrument, a part mounted to reciprocate on said pusher, and means operatively connected with said part for rotating said sheave against said holding means.

5. A recording mechanism for coke-oven pushers comprising a stationary recording instrument, a sheave mounted to rotate on said pusher, means for holding said sheave against rotation, an endless cable supported in frictional contact with said sheave so as to move with said pusher and operatively connected with said instrument, a part mounted to reciprocate on said pusher, and means operatively connected with said part for rotating said sheave against said holding means during the last stage of operation of said part.

6. A recording mechanism for coke-oven pushers comprising a stationary recording instrument, a cable anchored on the pusher and adapted to operate said instrument as the pusher moves, an extruding bar on the pusher and means operatively connected with said bar for imparting movement to said cable

during the last stage of operation of said bar.

7. A recording mechanism for coke-oven pushers comprising a stationary recording instrument, a cable anchored on the pusher and adapted to operate said instrument as the pusher moves, an extruding bar on the pusher, a levelling bar on the pusher and means operatively connected with said bars for imparting movement to said cable during the last stage of operation of said bars.

8. In an amperage recording mechanism for coke-oven pushers having a stationary recording instrument, a movable pusher, an extruding bar on the pusher, an electric motor on the pusher adapted to operate said bar, and means anchored on the pusher and adapted to operate said instrument for recording the amperage of said motor.

9. In an amperage recording mechanism for coke-oven pushers having a stationary recording instrument, a movable pusher, an extruding bar on the pusher, a levelling bar on the pusher, an electric motor on the pusher adapted to operate said bars, and means anchored on the pusher and adapted to operate said instrument for recording the amperage of said motor.

10. A recording mechanism for coke oven pushers comprising, a coke oven pusher, a stationary recording instrument, a device on said pusher for effecting operations in the ovens, and means anchored on the pusher and adapted to operate said instrument in the various positions of the pusher, said means being operatively connected with said device to effect the operation of said instrument.

In testimony whereof I affix my signature.
AUGUST KOPPERS.
